(57) **CLAIM**

The ornamental design for a combined electrical and mechanical connector, as shown and described.

DESCRIPTION

FIG. 1 is a top perspective view of an electrical and mechanical connector showing my new design.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a bottom view thereof.

FIG. 8 is a bottom perspective view thereof; and,

FIG. 9 is an exploded perspective view thereof.

The evenly spaced dashed lines represent unclaimed subject matter and form no part of the claimed design. The dot-dash broken lines define the bounds of the claimed design and form no part thereof.

The shade lines shown represent surface shading and not surface ornamentation.
